[57] CLAIM

The ornamental design for a surface protector stand, substantially as shown and described.

DESCRIPTION

FIG. 1 is a perspective view of the surface protector stand showing our new design;

FIG. 2 is a top plan view;

FIG. 3 is a side elevational view taken from the right side of FIG. 2, the opposite side being a mirror image;

FIG. 4 is a side elevational view taken from the bottom of FIG. 2, the opposite side being a mirror image;

FIG. 5 is a bottom plan view thereof.
